SELF-GRIPPING HAIR CURLER

William E. Thackeray, South Ogden, Utah, assignor to

Norman F. Agricola, Ogden, Utah

Filed Dec. 9, 1963, Ser. No. 329,104

8 Claims. (Cl. 132—40)

This invention relates to hair curlers, and more particularly to roller type curlers that do not require separate pins, clips, combs, or the like to insure a tight gripping of the hair while it is obtaining a desired set.

At the present time beauty shops, as well as many individuals, frequently use hair curlers consisting of smooth plastic or metal roller tubes in combination with separate gripping pins or clips. These curlers, while generally insuring a satisfactory curl if properly used, are difficult to use, especially for persons attempting to do their own hair. The hair must be smoothed around the tube as it is rolled on, and both hands are required to hold the hair and roller in position while the gripping device is attached. Furthermore, because of their small size, the clips, pins, or other gripping device are often lost, thus necessitating replacement of the entire curler, or at least of the gripping pins or clips.

Other popular hair curlers are made of rubber, wood, metallic mesh, or various other materials, and some of them have attached clamping devices for holding the hair in place. These have proven difficult to use, do not give a smooth set to the hair, and generally do not grip as firmly as is desired.

It is a principal object of the present invention to provide a hair curler wherein smooth roller tubes are provided with attached gripping means to securely clamp hair in place around them and wherein the gripping means is easily operated with the thumb and one finger of one hand.

Outstanding features of the invention include a smooth roller tube having a plurality of gripping means of tooth-like configuration protruding therethrough and actuator means for moving the gripping means between an open position wherein they extend outwardly from the roller tube and a closed position wherein they are securely locked against the outside of the roller tube.

There is shown in the accompanying drawing a specific embodiment of the invention representing what is presently regarded as the mode of carrying out the generic concepts in actual practice. From the detailed description of this presently preferred form of the invention, other more specific objects and features will become apparent.

FIG. 1 is a side elevation of a hair curler of the invention with the gripping means shown in open position;

FIG. 2, an end elevation, with the gripping means in open position;

FIG. 3, a side elevation, with the gripping means in closed or clamping position;

FIG. 4, an end elevation with the gripping means in clamping position;

FIG. 5, a central longitudinal section taken on line 5—5 of FIG. 2;

FIG. 6, a section taken on line 6—6 of FIG. 5; and

FIG. 7, a section taken on line 7—7 of FIG. 4.

Referring to the drawing:

In the illustrated preferred embodiment, the curler, shown generally at 10, includes a smooth tube 11 preferably made of plastic or metal, an actuator block 12, and a plurality of hair grippers 13 constructed of a material such as plastic having some degree of resiliency.

Tube 11 has a plurality of rows of holes 14 therethrough, and the hair grippers, of generally tooth-like

2

configuration, are placed in as many of the holes as desired. It has been found that hair grippers in two rows of holes give sufficient holding action to satisfy most users and that the other rows need not always be filled. If, however, extra holding strength is desired, additional hair grippers can readily be placed in any of the remaining holes. Furthermore, the spacing between holes in the rows can be varied as desired.

Each hair gripper, shown generally at 13, has a base portion 15 larger than the holes 14, and a contoured clamp portion 16, adapted to extend through the holes. A bend 17 is formed in the clamp portion 16 of each hair gripper adjacent its respective base 15, so that when it is in one over-center position its clamp portion will extend outwardly and substantially normal to the tube, as shown in FIGS. 1, 2, 5 and 6. In the other over-center position the clamping portions rest firmly against the side of the roller tube, as seen in FIGS. 3, 4 and 7.

The over-center movement of the hair grippers occurs when actuator block 12 is moved axially within tube 11, and the bases 15 of the hair grippers 13 are moved to either side of a center position normal to the common axis of the actuator and tube.

Shoulders 19 formed between clamp portions 16 and base portions 15 of the hair grippers abut the inner wall of the roller tube adjacent holes 14 through which the clamp portions extend, and act as pivots for the hair grippers. The bottom edges of the bases are positioned in grooves 20 formed in actuator 12, and the depth of the grooves is such that when bases 15 are in their centered position normal to the common axis of the tube and actuator, the distance between the bottom of the grooves and the inner wall of the roller tube just equals, or is slightly less than, the distance between the bottom edge of the bases 15 and the shoulders 19. This close fit of the bases within the spaces provided them insures a snap movement of the hair grippers from one position to the other and a locking of the hair grippers in position.

When the clamp portions of the hair grippers are extended, as shown in FIGS. 1 and 5, the actuator is prevented from moving to the right by the abutment of the groove walls with the base portions 15, and the abutment of the clamp portions 16 with the peripheries of holes 14. Undesired movement of the actuator to the left is prevented since extra force must be applied to move the base portions past their center position.

Similarly, when the hair grippers are in the position shown in FIGS. 3 and 6, movement of the actuator 50 to the left is prevented by the abutting relationship of the walls of grooves 20 with the base portions 15 and of the shoulders 19 with the inner wall of the roller tube. Undesired movement to the right is then prevented by resistance of the base portions to movement past their center position.

The actuator block 12 is formed to slidably fit within roller tube 11 and, in the form illustrated, has a plurality of flat sides forming chords across a portion of the inner circumference of the roller tube. To reduce the weight 60 and cost of the curler, the actuator block is preferably hollow and is made of plastic. One flat surface, extending the length of the actuator block, is provided for each row of gripping means used. As illustrated, for example, two rows of hair grippers are used, and flat sides 21 and 22 insure adequate clearance between the actuator 12 and tube 11 for placement of base portions 15 of hair grippers 13 therebetween. If it is desired to reduce the clearance between the block and the tube, in order to reduce the size bases required, for example, this can be 65 done by beveling the edges of the actuator block as at 12a, and utilizing a large block. Obviously, a round block flattened and grooved only where there are hair grippers,

or having larger and deeper V-grooves to receive base portions, could be used to achieve the same purpose as those illustrated.

When the actuator block is moved to the position shown in FIGURES 1, 2, 5 and 7, the hair grippers 13 are pivoted about their shoulders 21, moving clamp portions 16 until they extend substantially normal to the tube. While the hair grippers are in this position, they can be used in comb fashion and hair is easily rolled around the curlers.

Movement of actuator block 12 to the position of FIGS. 3, 4 and 6 causes the hair grippers 13 to pivot about their shoulders 21, and the clamp portions 16, because of their configuration, to lie against the outer surface of the tube, or against hair rolled around the tube, to hold it securely in place. The contoured shape of the clamping portions insures a better gripping action than is achieved with a straight extension.

Grooves 20 are preferably V-shaped to insure seating of base portions 15 therein, but it should be apparent that in some instances rounded grooves or grooves of other shapes could be employed. It is necessary, however, that the bottom edges of the base portions be engaged for movement with the actuator and that the groove allow sufficient freedom of movement for the hair grippers to pivot between its two locked positions.

In operation, the user rolls her hair around the tube in the conventional manner and then grasps the curler between thumb and finger of one hand. While holding the roller tube 11 at one end with the thumb, for example, the actuator is pushed into the tube at the opposite end, thereby moving the base portions "over-center" to lock the hair grippers in position. Obviously, if desired, the actuator could be provided with extensions protruding from one or both ends of the roller. These would serve as means for shifting the actuator by either pulling or pushing thereon.

The distance between the roller tube inner wall and the bottoms of the grooves in the actuator block and the size of the base portions, together with the amount of resiliency of the base portions of the gripping means, determines the amount of force needed to shift the actuator sufficiently to move the hair grippers "over-center." This force desirably is sufficient to prevent inadvertent opening of the hair grippers but not so great as to make opening by movement of the actuator block difficult for the user.

Whereas there is here illustrated and specifically described a certain preferred construction of apparatus which is presently regarded as the best mode of carrying out the invention, it should be understood that various changes may be made and other constructions adopted without departing from the inventive subject matter particularly pointed out and claimed herebelow.

I claim:

1. A hair curler, comprising a roller tube; gripping means at all times extending through the wall of said roller tube; actuator means in engagement with said gripping means; and cooperative locking means on said tube and said gripping means whereby reciprocation of said actuator means between first and second extreme positions through said tube moves said gripping means between a first positive locked position protruding from the tube and a second positive locked position lying substantially flat against the outer surface of said tube.

55
60
65

2. A hair curler as in claim 1, wherein the gripping means comprises hair grippers including clamp portions protruding from the tube and base portions within said tube, said clamp portions forming an angle with respect to said base portions and wherein the cooperative locking means comprises pivot surfaces on the base portions and the inner wall of the tube, said pivot surfaces engaging said inner wall to hold the hair grippers in locked positions.

10. 3. A hair curler as in claim 2, wherein the actuator means extends within the roller tube and engages the base portions of the hair grippers.

15. 4. A hair curler as in claim 2, wherein the actuator means includes an elongate member having grooves therein; the bottom edges of the base portions of the hair grippers being positioned in said grooves.

20. 5. A hair curler as in claim 4, wherein the pivot surfaces comprise shoulders formed on the base portions adjacent the clamp portions of the hair grippers, and wherein said shoulders cooperates with the inner wall of said roller tube to provide cooperating pivot surfaces for the hair grippers.

25. 6. A hair curler comprising a roller tube having spaced holes through the wall thereof; hair grippers including clamp portions extending through said holes and base portions within said roller tube, said base portions and said clamp portions defining an angle therebetween; a shoulder formed on each of said base portions adjacent the intersection of said clamp and base portions, said shoulders abutting the inner wall of said roller tube; an actuator block extending within said roller tube; means on said actuator block engaging said base portions, whereby movement of said actuator block along the axis of the roller tube will pivot said hair grippers about the shoulders thereof between a first locked position wherein said clamp portions extend outwardly from said roller tube and a second locked position wherein said clamp portions lie against the outer wall of the roller tube.

30. 7. A hair curler, comprising a roller tube; at least one hair gripper including a clamp portion protruding through the wall of the tube, and a base portion within said tube, said base portion including pivot surfaces engaging the inside wall of the tube; and actuator means including an elongate member having at least one groove therein, the bottom edge of said base portion being positioned in said groove, whereby movement of said actuator means moves said gripping means between a first locked position protruding outwardly from the wall of the tube and a second locked position lying substantially flat against the outer surface of said tube.

35. 8. A hair curler as in claim 7, wherein the pivot surfaces comprise shoulders formed on the base portion adjacent the clamp portion of the hair gripper.
